LOCOMOTIVE STOKER

Erwin Archer Turner, New York, N. Y., assignor to
The Standard Stoker Company, Incorporated,
a corporation of Delaware

Application June 4, 1938, Serial No. 211,847

5 Claims. (Cl. 110—105.5)

This invention relates to stokers and more particularly to locomotive stokers of the type that convey fuel from a source of supply, as from the tender, to the firebox through a firing opening in the locomotive boiler backhead, from which point the fuel is scattered over the fire by a pressure fluid blast.

It is an object of the invention to provide a stoker of the type described with efficient distributing means located in the firing opening and arranged to permit convenient manual delivery of fuel to the firebox and free access for entry thereto through the firing opening.

A more specific object is to provide, in a stoker which feeds fuel to one side of the firing opening only, a distributing means comprising a table from which fuel is projected over the firebed, the table occupying substantially the entire width of the firing opening and having a movable portion adapted to provide an unobstructed aperture along the opposite side of the firing opening whenever access into the firebox is desired.

It is also an object of this invention to hinge the movable portion of such table to the main portion thereof by linkage which normally forms a firm support for the movable portion of the table.

Other objects and their attendant advantages will become apparent as the following description of the invention is read in connection with the accompanying drawings, in which

Fig. 1 is a sectional plan view through the portion of the locomotive boiler backhead that includes the firing opening with a firedoor applied thereto, a portion of the firedoor being broken away showing a portion of the stoker in plan view;

Fig. 2 is a side elevation of the stoker and firedoor structure illustrated in Fig. 1 with parts broken away and shown applied to the locomotive boiler backhead, the latter being shown in vertical medial section;

Fig. 3 is a view in elevation of the stoker from within the firebox, showing the stoker applied to the firing opening of the boiler backhead; and

Fig. 4 is a view similar to the view of the structure in Fig. 1 showing a modified form of the invention.

With reference first to the preferred embodiment of the invention illustrated in Figures 1 to 3, inclusive, A indicates a locomotive having a boiler 10 provided with a firebox 11 which extends forwardly from the hollow backwall 12. The latter is provided with a firing opening 13

adapted for the supply of fuel therethrough by power or manual means. The firing opening 13 is of sufficient size so that a stoker S may deliver fuel through the side R of such opening while the side L is arranged to permit feeding of fuel by manual means and also for the purpose of gaining access to the interior of the firebox 11.

The stoker S includes a riser conduit 20 which slopes upwardly and forwardly to the firing opening 13 and houses a conveyor screw 21 for urging fuel through said riser conduit 20 and into the zone of action of a distributor D. At its forward end the riser conduit 20 discharges into the upper side R of the firing opening 13. The distributor D includes a jet member 22 which forms the forward end of the riser conduit 20 and is fastened to the main section of said riser conduit 20 by bolts 23. A plurality of chambers such as 24 are formed in the jet member 22 for receiving fluid under pressure, from a suitable source, delivered by supply lines 25. The forward side 26 of the jet member 22 is provided with a plurality of jet apertures 27 leading from chambers 24 and arranged to issue blasts of pressure fluid across a table 28 extending in a forward direction from a point below the level of the jet apertures 27.

It is well known that a helicoid screw, such as that designated by the reference numeral 21 in the drawings, will deliver more coal to one side of its axis than to the other. The screw 21, having flights which are wound to advance fuel when rotated in a clockwise direction, as viewed in the direction of flow, delivers most of its charge to the left side of its axis. Referring particularly to Figure 1, it will be observed that the screw 21 delivers most of its charge toward the side of the firebox marked L. Thus, the greater charge of fuel delivered toward the side L will compensate for offsetting the riser conduit 20 and jet member 22 toward the side R and even distribution of fuel over the firebed is attained.

However, since the greater charge of fuel is delivered to the left side of the distributor table 28, the latter includes a portion 29 which extends laterally from the main portion 30 to occupy space at the side L of the firing opening 13, which is reserved for gaining access into the firebox 11. Accordingly, the portion 29 of the distributor table 28 is so arranged with the main portion 30 thereof that it may be readily removed from its position at the side L of the firing opening 13.

On its underside, the portion 29 is provided with a pair of spaced ears 31, 32, each of which extends beneath the main portion 30 of the table 28 so as to straddle a lug 33 formed with the main portion 30. A pin 34 is passed through the ears 31, 32 and the lug 33, forming a hinge connection between the portions 29 and 30 of the table 28. In order to support the portion 29 in its operative position an articulated link 35 is utilized and it consists of a lower link section 36 and an upper link section 37 connected by a pin 38. The upper link section 37 is connected at 39 to a lug 40 which depends from the underside of the table portion 30, while the lower link section 36 is connected by a pin 41 to a bracket 42 secured to a wall 43 depending from the underside of the riser conduit 20. Adjacent the pin 38, the upper link section 37 is provided with a stop element 44 which engages the lower link section 36 in order to prevent downward movement of the articulated link 35. In normal position, the link sections 36 and 37 make an obtuse angle of less than 180° with each other on that side of the articulated link 35 which carries the stop element 44. This construction is desirable in order to prevent accidental displacement of the link 35 from sudden shocks of the locomotive while in operation.

Whenever access to the interior of the firebox 30 is desired, the firedoor F is thrown open and the operator lifts the articulated link 35 upwardly at the joint formed by the pin 38 and stop element 44. This serves to break this joint and permits the link sections 36, 37 and table portion 29 to assume the positions indicated by the dot and dash lines in Figure 3. When these parts are in this position there is formed an unobstructed aperture along the entire side L of the firing opening 13 which is of ample size to permit free access into the firebox 11.

In the modification illustrated in Figure 4, the table portion 29 is provided with an elongated lug 50 apertured to receive one end of a long pin 51 for maintaining the table portion in its operative relation. The pin 51 passes through a bearing 52 formed in a wall 53 of the riser conduit 54 and is preferably sloped downwardly to prevent its casual displacement. On its outward end, the pin 51 has an enlarged head 55 which limits forward movement thereof. The head 55 may carry a bail 56 for manual withdrawal of the pin 51 from engagement with the lug 50 whereby the table portion 29 will swing out of the way in the firing opening 13.

To those familiar with the art, it will be apparent that an efficient distributor has been provided for a stoker of the type described, the distributor being arranged to permit unobstructed access into the firebox. Certain features of this invention, it will be understood, are of utility in stokers of other types.

I claim:

1. In a furnace having a wall with a firing opening therein and a stoker for feeding fuel to said furnace through one lateral side of said firing opening only, said stoker comprising a conduit in communication with said furnace and a distributor positioned at said firing opening for receiving fuel from said conduit, said distributor including a table extending across the major portion of said firing opening at each side of the longitudinal vertical medial plane thereof and arranged to support fuel discharged by said conduit, and a jet member at one lateral side only

of said firing opening for projecting forwardly the fuel supported upon said table, said table including a portion occupying space within one lateral side of said firing opening approximately coextensive with said jet member, and a portion, 5 in operative position, occupying space within the opposite lateral side of said firing opening, said last named portion being movable from its operative position to provide an unobstructed space in said last named lateral side of the firing opening. 10

2. In a furnace having a wall with a firing opening therein and a stoker for feeding fuel to said furnace through one lateral side of said firing opening only, said stoker comprising a conduit in communication with said furnace and a distributor positioned at said firing opening for receiving fuel from said conduit, said distributor including a table extending across the major portion of said firing opening at each side of the 20 longitudinal vertical medial plane thereof and arranged to support fuel discharged by said conduit, and a jet member at one lateral side only of said firing opening for projecting forwardly the fuel supported upon said table, said table including a portion occupying space within one lateral side of said firing opening approximately coextensive with said jet member, and a portion, 25 in operative position, occupying space within the opposite lateral side of said firing opening, said last named portion being hinged to said first named portion and being movable from its operative position to provide an unobstructed space in said last named lateral side of the firing opening, and means for supporting said last named portion in an operative position. 30

3. In a furnace having a wall with a firing opening therein and a stoker for feeding fuel to said furnace through one lateral side of said firing opening only, said stoker comprising a conduit in communication with said furnace and a distributor positioned at said firing opening for receiving fuel from said conduit, said distributor including a table extending across the major portion of said firing opening at each side of the 40 longitudinal vertical medial plane thereof and arranged to support fuel discharged by said conduit, and a jet member at one lateral side only of said firing opening for projecting forwardly the fuel supported upon said table, said table including a portion occupying space along one lateral side of said firing opening approximately coextensive with said jet member, and a portion, 45 in operative position, occupying space along the opposite lateral side of said firing opening, said last named portion being hinged to said first named portion, and means for supporting said last named portion in an operative position, said means including an articulated link being yieldable between its ends in one direction only. 50

4. In a furnace having a wall with a firing opening therein and a stoker for feeding fuel to said furnace through one lateral side of said firing opening only, said stoker comprising a conduit 65 in communication with said furnace and a distributor positioned at said firing opening for receiving fuel from said conduit, said distributor including a table extending across the major portion of said firing opening at each side of the 70 longitudinal vertical medial plane thereof and arranged to support fuel discharged by said conduit, and a jet member at one lateral side only of said firing opening for projecting forwardly the fuel supported upon said table, said table includ- 75

ing a portion occupying space along one lateral side of said firing opening approximately coextensive with said jet member, and a portion, in operative position, occupying space along the opposite lateral side of said firing opening, said last named portion being hinged to said first named portion, and means for supporting said last named portion in an operative position, said means including an articulated link at one end connected to said portion and at its opposite end being supported against movement bodily, said link being yieldable between its ends in one direction only.

5. In a furnace having a wall with a firing opening therein and a stoker for feeding fuel to said furnace through one lateral side of said firing opening only, said stoker comprising a conduit in communication with said furnace and a distributor positioned at said firing opening for

receiving fuel from said conduit, said distributor including a table extending across the major portion of said firing opening and arranged to support fuel discharged by said conduit, and a jet member at one lateral side of said firing opening for projecting forwardly the fuel supported upon said table, said table including a portion occupying space along one lateral side of said firing opening approximately coextensive with said jet member, and a portion, in operative position, occupying space along the opposite lateral side of said firing opening, said last named portion being hinged to said first named portion, and means engaging said portion for supporting the latter in operative position, said means being controlled outside of said furnace for disengaging said portion.

EDWIN ARCHER TURNER.
